UNITED STATES PATENT OFFICE.

HERMAN GASSTROM, OF NEW YORK, N. Y., ASSIGNOR TO DAHL MANUFACTURING COMPANY, OF NEW YORK, N. Y., A CORPORATION OF NEW YORK.

STRUCTURE MADE OF RELATIVELY MOVABLE AND INTERLOCKING SECTIONS.

1,159,012.

Specification of Letters Patent. Patented Nov. 2, 1915.

Application filed February 11, 1913. Serial No. 747,693.

To all whom it may concern:

Be it known that I, HERMAN GASSTROM, a subject of the Czar of Russia, and a resident of the city of New York, borough of 5 Manhattan, in the county and State of New York, have invented new and Improved Structures Made of Relatively Movable and Interlocking Sections, of which the following is a specification.

10 This invention relates to new and useful improvements in relatively movable and interlocking sections, the advantages following the use of such sections appearing more fully as the description thereof proceeds, 15 the inventive idea being comprehended within the scope of the appended claims.

The inventive idea is capable of application to a variety of structures adapted for different uses; while I have illustrated one 20 particular use in the accompanying drawings, and have described the relation of the parts adapted to such use, it is, of course, clear that such construction is merely typical of the idea disclosed.

25 Reference is to be had to the accompanying drawings forming a part of this specification, in which like characters of reference indicate corresponding parts in all the views, and in which—

30 Figure 1 is a plan view of the top section of a rule. Fig. 2 is a side elevation of a rule. Fig. 3 is sectional view on a line 3—3 of Fig. 1. Fig. 4 is a longitudinal sectional view showing the parts in lock and 35 closed position. Fig. 5 is a similar view showing the rule in the act of extension and unlocking. Figs. 6 and 7 represent plan views of the coöperating locking devices.

As shown in the drawings: the rule consists 40 of a number of sections A, B, C and D, each provided with a grooved side, such as one extending throughout the length of the rule, each section having a pocket through its body to contain one of the locking elements to be hereinafter described. Each section has the locking elements secured 45 permanently to it, and is provided with engaging members to slide in the groove of the next adjacent section.

50 Each intermediate section is the same. One extreme section is provided with a pocket near its mid portion containing a locking mechanism, and the other extreme section is like the intermediate sections, ex-

cept that its free end does not have any 55 locking mechanism.

The locking members for the pockets 2 at the left hand side of Figs. 4 and 5 consist of the plates 6 fastened by prongs 100, into the body of the wood of its section, and provided with curved and bent slide arms 8 to engage the slot of the adjacent section. The plate 6 carries stamped-up bearing pieces 9, in which on an axis 11 a locking lever 10 is mounted. The locking lever 10 is 60 bent as shown at Fig. 4, to normally exert a spring action on the lever 10 to project the nose 13 of the lever through the opening surrounded by the metal guard 30, and to project the end 12 upwardly so that when it 65 reaches an opening 21 in the section immediately above it it will enter such opening.

The locking member in the bottom section is similar to that just described. At the right of the rule as shown in the drawings, 75 each section is provided with a plate 16, having engaging prongs 18 to slide in the adjacent member, bent up trunnions 24 for a shaft 23, of a lever 22, and prongs 100 to engage the wood of its section. This plate 80 16 carries an inclined slide 17 at one end, and in line with it an aperture 21 shown in dotted lines, Fig. 7, over which aperture one end of a lever 22 normally lies, the end 85 of which is fashioned as a spring 26 to keep the nose 25 of the locking lever 22 projected not only past the guard ring 5 of its own section but into an aperture 20 of the adjacent section, so that normally the nose 25 projecting past the aperture in two ad- 90 joining sections will lock the rule sections against movement.

In order to unlock the sections and permit the rule to be used, but to permit only one section at a time to be moved, the section A 95 is provided, so that it may always move to and fro after it is unlocked. Upon moving it to the right in Fig. 4 the end 12 will project through the opening 21, lift the lever 22, cause the nose 25 to be withdrawn, and 100 as this happens at the completion of the movement of section A, the section B will then be free to be moved to the right until the nose 12 on the left hand locking mechanism on section B disengages the nose 25 of 105 the locking means at the right of section C, and so on until all the sections are disengaged. When the sections are extended and

disengaged, one cannot after that collapse any of the sections unless he begins with the section A, depressing the nose 13 to disengage the locking end of the lever 10 from its position through the orifice 21 in the plate 16. When that is done, the section A may be returned to the left, but at the end of the returning trip the section itself depresses the nose 13 of section B, and releases 10 its hooked end 12 from engagement with section C.

It will thus be seen that the sections are locked with the exception of section A, when in closed position, and can only be unlocked 15 upon movement of section A. The sections are locked in extended position even including section A, which can only be unlocked manually and after which on sliding section A the others will be automatically unlocked 20 successively, and permitted to move by the successive closing of the sections themselves.

In order to effect what is known as inside 25 and outside readings, the inside reading being clearly set forth in my United States Letters Patent No. 978,446, dated December 13th 1910, I only permit movement of the section A for a less distance along the section B than I permit the other sections, and for this purpose I provide the stops 7 and 8 30 on section A that their movement will be stopped when they come in contact with the metal portion 19 at the right of the rule.

In carrying out this invention, details of 35 construction may be varied from those shown, and yet the essence of the invention may be retained; some parts might be employed without others, and new features thereof might be combined with elements old in the art in diverse ways, although the herein described type is regarded as embodying substantial improvements over such 40 modifications.

Copies of this patent may be obtained for five cents each, by addressing the "Commissioner of Patents, Washington, D. C."

As many changes could be made in the above construction, and many apparently widely different embodiments of the invention could be made without departing from the scope thereof, it is intended that all matter contained in the above description or shown in the accompanying drawings 45 shall be interpreted in an illustrative and 50 not in a limiting sense.

It is furthermore desired to be understood that the language used in the following claims is intended to cover all the generic and specific features of the invention herein 55 described, and all statements of the scope of the invention which as a matter of language might be said to fall therebetween.

I claim as my invention:

1. In a device consisting of a number of 60 members sliding one on the other, locking means between adjoining sections adapted to automatically lock one section against movement with its adjoining section upon the mere extension of the device, the manual 65 means for unlocking one section and automatic means operated by the movement of one section along the next to unlock further sections successively.

2. In a device consisting of a number of 70 members sliding one upon the other, locking means between adjacent sections adapted on the mere extension of one section to lock it against collapse, and unlocking devices initially manually controlled to permit thereafter successive collapse of all sections automatically. 75

In testimony whereof I have signed my name to this specification in the presence of two subscribing witnesses.

HERMAN GASSTROM.
